EXCAVATING-MACHINE.

1,234,672.

Specification of Letters Patent. Patented July 24, 1917.

Application filed November 11, 1916. Serial No. 130,841.

To all whom it may concern:

Be it known that I, LEO A. KRUPP, a citizen of the United States, and a resident of Findlay, in the county of Hancock and State 5 of Ohio, have invented a certain new and useful Excavating-Machine; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to excavating machines and particularly to those of the cutting-wheel open ditch digging type.

The primary object of my invention is the provision of a machine of the class described 20 adapted for digging trenches of narrow gage for receiving water, gas and other conduits of small diameter, and also adapted for digging in close quarters.

Further objects of my invention are the 25 provision of an excavating-wheel having improved buckets thereon adapted for narrow gage work, and the provision of simple and improved means for successively cleaning or ejecting the dirt or contents from the 30 buckets as the wheel is rotated.

Further objects and advantages of the invention will be apparent from the following detailed description thereof.

While the invention, in its broader aspect, 35 is capable of embodiment in numerous forms, a preferred embodiment thereof is illustrated in the accompanying drawings, in which,—

Figure 1 is a side elevation of a machine 40 embodying the invention with the cutter-wheel in lowered trench digging position. Fig. 2 is an enlarged elevation of the rear end portion of a machine with parts broken away and with the tractor in section on the line 2—2 in Fig. 6. Figs. 3 and 4 are enlarged sections on the lines 3—3 and 4—4, respectively, in Fig. 2. Fig. 5 is an end view of the bucket cleaning member. Fig. 6 is a top plan view of the portion of the 50 machine shown in Fig. 2. Fig. 7 is a section on the line 7—7 in Fig. 6, and Fig. 8 is a fragmentary perspective view of a portion of the machine driving means with parts in section.

55 Referring to the drawings, 1 designates

the main frame of a tractor having the rear drive wheels 2 and the front steering wheels 3. The drive wheels 2 are mounted on the respective ends of an axle 4, which is journaled in bearings carried by the rear end 60 portion of the frame 1, one of said wheels being fixed to the shaft and the other loose on the shaft. A large gear 5 is fixed on the axle 4 and has driving connection with the loose drive wheel through the medium of a 65 differential gearing 6.

A pair of standards 7 rise in transversely spaced relation from the rear end of the tractor frame 1, being forwardly connected to the frame and braced with respect thereto 70 by bars 8, and also having suitable transverse connection, not shown. A shaft 9 is mounted above the axle 4 in suitable bearings 10 provided on the respective standards 7, and this shaft carries a sprocket-wheel 11 75 having chain connection 12 with a drive sprocket-wheel 13, and also carries a pinion 14 in mesh with the gear 5 at its top edge. The sprocket-wheel 13 is mounted on a shaft 15, which is suitably journaled in the tractor frame 1 transversely thereof and carries a beveled gear 16 in mesh with a drive pinion 17 on the main drive or motor shaft of the vehicle, the motor being designated 18. The pinion 14 is loose on the shaft 9 and a clutch-collar 19 is splined on the shaft at one side of said pinion and is shiftable into and out of engagement therewith, as it may be desired to permit the pinion to run idle or to place it in driving connection with the shaft. 80

A shaft 20 is mounted on the frame 1 transversely thereof at the rear of the shaft 15 and carries a pinion 21 at one end in mesh with the gear 5, and a ratchet-wheel 22 at its other end. The pinion 21 is loose on the shaft 20, and the clutch member 23 is splined on the shaft at the outer side of the pinion and is movable into and out of engagement therewith. It is intended that only one of the pinions 14 and 21 shall be in clutch engagement with its shaft at the same time so that the gear 5 will either be driven from the shaft 9 or from the shaft 20, one shaft being employed for driving purposes when traveling from place to place. The driving of the machine is through the shaft 9 and pinion 14 when it is desired to rapidly move the machine as, for instance, in traveling from one job to another, and the drive is through the shaft 20 and pinion 21 when 100 105 110

it is desired to impart slow forward feeding movements to the machine while digging.

The shaft 9 has an eccentric stud 24 at the end thereof adjacent to the ratchet-wheel 22, and an eccentric-rod 25 projects from said stud and is pivotally connected at its free end to a rocker-arm 26 over the ratchet wheel, said arm being journaled for free rocking movements on the shaft 20. A pawl 27 is carried by the pivot which connects the members 25 and 26 and coacts with the ratchet teeth to impart intermittent rotary movements to the ratchet wheel when the pawl is moved in one direction. The ratchet-wheel 22 is locked against back turning movements by a dog 28 engaging the teeth thereof.

The eccentric stud 24 is carried by the shaft 9 for adjustment transversely thereof to enable the throw of the eccentric to be varied to suit the speed at which it is desired to drive the shaft 20. For this purpose the stud 24 is provided at its inner end with a flanged head 29, which fits into a transverse recess 30 in the shaft end. A bearing sleeve 31 encircles the stud 24 and cooperates with a nut 32 on the outer end of the stud to clamp the stud in adjusted relation to the shaft. The eccentric rod has one end sleeved loosely on the bearing sleeve 31.

The frame 1 is provided at its rear end between its side beams with a pair of transversely spaced bearings 33, 33 in which a shaft 34 is journaled, said shaft having a sprocket-wheel 35 fixed to one end thereof and connected by a chain 36 to a sprocket-wheel 37, which is loosely mounted on the shaft 9 (Figs. 2 and 6). A clutch member 38 is splined on the shaft 9 at one side of the sprocket-wheel 37 and is adapted to be moved into and out of clutch engagement with the hub of such sprocket-wheel.

A cutter-wheel carrying frame 39 is pivotally carried at its inner or forward end by the shaft 34 for vertical swinging movements with respect to the tractor frame 1. The frame 39 comprises the opposite side beams 39^a, 39^a, which are longitudinally angled, as shown, and these beams carry a superframe 39^b for supporting the bucket cleaning mechanism, as hereinafter described.

An excavating wheel 40 is carried for free rotary movements by the frame 39 between the side beams thereof and has the rim 41, which is T-form in cross-section with the leg flange thereof extending inward, as shown in Figs. 3 and 4. A plurality of segmental plates 42 are secured together in opposed relation and in successive order entirely around the inner edge of the rim 41, and form sets of rack teeth 43 at each side of the leg flange of the wheel rim. The plates 42 also extend around the

inner edge of said flange and form an annular surface or rail for coacting with the groove carrier wheels 44, one of which is carried by a subjacent frame part 39^c on the frame 39, while the others are carried by cross-shafts on the beams 39^a. The wheels 44 carry and guide the rotary movements of the cutter-wheel 40 and one wheel is mounted on a drive shaft 45 and has its peripheral side flanges forming gears which mesh with the teeth 43 on the respective sides of the wheel rim so that a rotation of the toothed wheel will impart rotation to the excavating wheel. The shaft 45 extends through the interior of the wheel 40 being mounted in suitable bearings on the beams 39^a transversely thereto. Sprocket-wheels 46 and 47 are fixed to the outer ends of the shaft 45 without the beams 39^a, and the sprocket-wheel 46 is connected by a sprocket-chain 48 to a sprocket-wheel 49 on one end of the shaft 34.

The periphery of the wheel 40 is provided with equidistantly spaced cutter blades 50, which blades curve outward and forward from the wheel periphery in the direction of cutting rotation of the wheel (as shown in Fig. 2) and have their outer end portions transversely broadened and sharpened to form cutting edges with such edges preferably turned slightly outward as indicated. The blades 50 also have their body portions preferably slightly concaved in cross-section, as indicated in Fig. 2. The inner end portions of the blades 50 are equal or substantially equal in width to the width of the wheel periphery and the broadening of the outer end portions of the blades causes the trench dug thereby to be slightly wider than the wheel periphery.

Side plates 51 are carried by the sub-frame 39^c at opposite sides thereof with their outer sides substantially aligned or flush with the respective broadened side edges of the blades 50 so that said blades have sliding contact with the wheels of the trench, or substantially so, as the digging progresses. The blades 51 are intended to substantially close the portion of the cutter-wheel opening disposed below the ground line, thus preventing loose dirt from falling into the wheel from the sides of the trench.

A shaft 52 is mounted in the super-frame 39^b above the cutter-wheel 40 lengthwise of the machine and has an arm 53 feathered thereon for turning movements therewith. This arm is provided at its free end with a cleaner blade 54 of suitable shape for a part thereof to pass under a registering blade 50 of the cutter-wheel and discharge the dirt or other matter carried upward thereby transversely from the wheel. The shaft 52 has rotation communicated thereto from the sprocket wheel 47 through the medium of the chain 55, sprocket-wheel 56, shaft 57 and 130

- bevel gears 58 and the turning of the shaft 52 is so timed that the cleaner blade 54 is caused to swing under each cutter blade 50 as it moves into dirt discharging position at the top of the cutter-wheel. The forward movement of the arm 53 on the shaft 52 is limited by a collar 59 on said shaft and a coiled compression spring 60 on said shaft normally retains the arm in yielding contact with said collar. The purpose of mounting the arm 53 to have rearward yielding movements is to permit it to pass any obstructions during a blade cleaning movement.
- 5 The dirt and other matter which is discharged from the cutter-wheel blades by the cleaner member 54 is deposited on a delivery chute 61 and directed thereby to one side of the trench being dug. The chute 61 is carried by the frame 39.
- 10 The frame 39 and mechanism carried thereby are raised and lowered with respect to the tractor frame 1 by a cable 62, which is fixed at one end to the upper portions of the standards 7—7, thence extends around a sheave 63 carried by the frame 39 at its outer end, and over a sheave 64 at the upper end of the standard 7 and down to and around a drum 65. This drum is mounted 15 in a frame 66 and has its turning controlled by a hand-wheel 67, which is in suitable connection therewith (not shown). It is evident that the cutter-wheel carrying frame may be raised or lowered without disconnecting the driving connection between the motor and the wheel, as the swinging movements of the frame are about the shaft 34 as a center, which shaft is in chain connection both with the cutter-wheel driving 20 shaft 45 and with the motor driven shaft 9.
- 15 In the use of my machine the cutter-wheel is gradually lowered into the ground until it obtains the desired depth of cutting, such lowering of the cutter-wheel being controlled by a turning of the hand-wheel 67, and when the desired depth of cut has been reached, the tractor and cutter-wheel are slowly moved forward by throwing the clutch 23 into engagement with the pinion 21 so that 25 a forward driving movement is communicated to the gear wheel 5 and thence to the tractor wheels from the slow speed shaft 20. This shaft has intermittent turning movements in a forward feeding direction imparted thereto from the shaft 9 through the medium of the rod 29, which is eccentrically connected to the shaft 9 and through the pawl 27 and ratchet-wheel 22. The cutter-wheel 40 is driven from the shaft 9 by throwing 30 the clutch member 38 into engagement with the sprocket-wheel 37, from which rotation is communicated to the shaft 34 and thence to the cutter-wheel driving shaft 45. The shaft 45 is in turn connected to the 35 cleaner shaft 52 and drives the latter at a speed suitable for turning the cleaner blade 54 a number of times corresponding to the number of cutter blades 50 on the cutter-wheel for each revolution of said wheel, the turning movements of the cleaner blade 54 being so timed with respect to the turning of the cutter-wheel that the blade passes through the space between each blade and the cutter-wheel rim and discharges the dirt or other matter from the blade transversely of the wheel and onto the delivery chute 61. When the machine is being transported from one place to another and the cutting-wheel is elevated in inoperative position, the driving action is communicated directly from the shaft 9 to the gear 5 through the medium of the pinion 14, which is then in clutch engagement with its shaft, and the clutch 38 is disengaged from the sprocket wheel 37 to prevent a driving of the cutter-wheel.
- 40 The dirt and other matter which is discharged from the cutter-wheel blades by the cleaner member 54 is deposited on a delivery chute 61 and directed thereby to one side of the trench being dug. The chute 61 is carried by the frame 39.
- 45 The frame 39 and mechanism carried thereby are raised and lowered with respect to the tractor frame 1 by a cable 62, which is fixed at one end to the upper portions of the standards 7—7, thence extends around a sheave 63 carried by the frame 39 at its outer end, and over a sheave 64 at the upper end of the standard 7 and down to and around a drum 65. This drum is mounted 50 in a frame 66 and has its turning controlled by a hand-wheel 67, which is in suitable connection therewith (not shown). It is evident that the cutter-wheel carrying frame may be raised or lowered without disconnecting the driving connection between the motor and the wheel, as the swinging movements of the frame are about the shaft 34 as a center, which shaft is in chain connection both with the cutter-wheel driving shaft 45 and with the motor driven shaft 9.
- 55 In the use of my machine the cutter-wheel is gradually lowered into the ground until it obtains the desired depth of cutting, such lowering of the cutter-wheel being controlled by a turning of the hand-wheel 67, and when the desired depth of cut has been reached, the tractor and cutter-wheel are slowly moved forward by throwing the clutch 23 into engagement with the pinion 21 so that 60 a forward driving movement is communicated to the gear wheel 5 and thence to the tractor wheels from the slow speed shaft 20. This shaft has intermittent turning movements in a forward feeding direction imparted thereto from the shaft 9 through the medium of the rod 29, which is eccentrically connected to the shaft 9 and through the pawl 27 and ratchet-wheel 22. The cutter-wheel 40 is driven from the shaft 9 by throwing 65 the clutch member 38 into engagement with the sprocket-wheel 37, from which rotation is communicated to the shaft 34 and thence to the cutter-wheel driving shaft 45. The shaft 45 is in turn connected to the cleaner shaft 52 and drives the latter at a speed suitable for turning the cleaner blade 54 a number of times corresponding to the number of cutter blades 50 on the cutter-wheel for each revolution of said wheel, the turning movements of the cleaner blade 54 being so timed with respect to the turning of the cutter-wheel that the blade passes through the space between each blade and the cutter-wheel rim and discharges the dirt or other matter from the blade transversely of the wheel and onto the delivery chute 61. When the machine is being transported from one place to another and the cutting-wheel is elevated in inoperative position, the driving action is communicated directly from the shaft 9 to the gear 5 through the medium of the pinion 14, which is then in clutch engagement with its shaft, and the clutch 38 is disengaged from the sprocket wheel 37 to prevent a driving of the cutter-wheel.
- 70 The dirt and other matter which is discharged from the cutter-wheel blades by the cleaner member 54 is deposited on a delivery chute 61 and directed thereby to one side of the trench being dug. The chute 61 is carried by the frame 39.
- 75 The frame 39 and mechanism carried thereby are raised and lowered with respect to the tractor frame 1 by a cable 62, which is fixed at one end to the upper portions of the standards 7—7, thence extends around a sheave 63 carried by the frame 39 at its outer end, and over a sheave 64 at the upper end of the standard 7 and down to and around a drum 65. This drum is mounted 80 in a frame 66 and has its turning controlled by a hand-wheel 67, which is in suitable connection therewith (not shown). It is evident that the cutter-wheel carrying frame may be raised or lowered without disconnecting the driving connection between the motor and the wheel, as the swinging movements of the frame are about the shaft 34 as a center, which shaft is in chain connection both with the cutter-wheel driving shaft 45 and with the motor driven shaft 9.
- 85 The dirt and other matter which is discharged from the cutter-wheel blades by the cleaner member 54 is deposited on a delivery chute 61 and directed thereby to one side of the trench being dug. The chute 61 is carried by the frame 39.
- 90 The frame 39 and mechanism carried thereby are raised and lowered with respect to the tractor frame 1 by a cable 62, which is fixed at one end to the upper portions of the standards 7—7, thence extends around a sheave 63 carried by the frame 39 at its outer end, and over a sheave 64 at the upper end of the standard 7 and down to and around a drum 65. This drum is mounted 95 in a frame 66 and has its turning controlled by a hand-wheel 67, which is in suitable connection therewith (not shown). It is evident that the cutter-wheel carrying frame may be raised or lowered without disconnecting the driving connection between the motor and the wheel, as the swinging movements of the frame are about the shaft 34 as a center, which shaft is in chain connection both with the cutter-wheel driving shaft 45 and with the motor driven shaft 9.
- 95 While I have herein shown and described one specific modification of my invention for illustrative purposes, and have disclosed and discussed in detail the construction and arrangement incident to one specific application thereof, it is to be understood that the invention is not limited to the mere detail or relative arrangement of the parts, but that deviations from the illustrated form or body 100 of the invention may be made without departing from the spirit of the claims.
- 100 Having thus described my invention, what I claim as new, and desire to secure by Letters Patent, is,—
- 110 1. In a machine of the class described, an excavating-wheel, a blade mounted on the periphery of said wheel, a revoluble blade cleaning member mounted for yielding axial movements, and means operable to move said member to periodically discharge matter from the blade transversely of the wheel.
- 115 2. In a machine of the class described, an excavating-wheel having a blade on its periphery, a cleaner member mounted for revoluble movements transversely of the wheel periphery and for axial yielding movements transverse to the wheel axis, and means operable to revolve said member and cause it to have cleaning coöperation with said 120 blade at each revolution of the blade.
- 120 3. In a machine of the class described, an excavating-wheel having a plurality of blades mounted on its periphery in successive order and extending outward and for- 125
- 130 65

4
ward thereof in the direction of rotation of the wheel, a shaft mounted over said wheel transverse to its axis, a cleaner member carried by said shaft for revoluble movements therewith and yielding movements lengthwise thereof and adapted to pass between a blade and the wheel periphery trans-

versely of the latter, and means for driving said shaft to move said member between each blade and the wheel periphery as the blades 10 successively move into discharging position.

In testimony whereof, I have hereunto signed my name to this specification.

LEO A. KRUPP.
